TOY HELMET WITH REVOLVING STREAMER

Bryce L. Loudon, 9121 Kendrick Way, Orangevale, Calif.,
and Kenneth R. De Giorgis, 3917 Arrowhead Drive,
El Dorado Hills, Calif.

Filed Feb. 28, 1966, Ser. No. 1,215

Term of patent 14 years

(Cl. D3—13)

FIG. 3

FIG. 4

FIG. 5

FIGURE 1 is a top plan view of a toy helmet with revolving streamer showing our new design;

FIGURE 2 is a front elevational view;

FIGURE 3 is a sectional view, the planes of the section being indicated by the line 3-3 in FIGURE 2;

FIGURE 4 is a bottom plan of the helmet; and,

FIGURE 5 is a perspective view thereof shown on a reduced scale, the showing of the head of a wearer being for purposes of illustration only.

We claim:

The ornamental design for top helmet with revolving streamer, as shown and described.
